UNITED STATES PATENT OFFICE.

GRADY L. BARNETT, OF STRATFORD, TEXAS.

WATER-ELEVATOR.

1,323,146.

Specification of Letters Patent. Patented Nov. 25, 1919.

Application filed May 19, 1919. Serial No. 298,064.

To all whom it may concern:

Be it known that I, GRADY L. BARNETT, a citizen of the United States, residing at Stratford, in the county of Sherman and 5 State of Texas, have invented new and useful Improvements in Water-Elevators, of which the following is a specification.

Pumps employed in arid districts for irrigating purposes are generally of a complicated nature, extremely costly in manufacture and installation, frequently become disordered, which requires a great amount of time and labor for the making of the proper repairs, and in other respects present deficiencies.

The main objection, however, to such class of pumps is the high cost in purchase, operation and maintenance, and it may therefore be considered the primary object of the 20 present invention to produce a high power water elevating means which will insure a steady and voluminous flow of water that may be manufactured and installed comparatively cheap and which entirely dispenses with the reciprocatory pistons, the massive framework on the ground surface and the intricate mechanism for operating the pistons.

In carrying out my invention it is my 30 purpose to close the well above the water level, to force a volume of air continuously in the water compartment, to provide an outlet pipe for the water leading through the closure and to provide means in said 35 outlet pipe, operative exteriorly of the well for imparting a rotary or centrifugal motion to assist in raising the water through the outlet pipe.

Other objects and advantages of my improvement will appear as the nature thereof is more fully understood, reference is to be had to the accompanying drawings in which there is illustrated a simple and satisfactory embodiment of the improvement 45 reduced to practice, it being understood, however, that the nature of the invention is such as to render the same susceptible to all such modifications as fall within the scope of what is claimed.

50 In the drawings:

Figure 1 is an elevation, parts being broken away and parts being in section, illustrating the improvement.

Fig. 2 is an enlarged vertical longitudinal 55 sectional view through the lower portion or mouth of the water outlet pipe.

While in arid districts the earth's surface is dry and will not accommodate vegetation, a great amount or volume of water is always found at suitable distances below 60 the earth's surface whereby the ground may be properly irrigated and vegetation assured.

As disclosed in Fig. 1 of the drawings, I dig a well which is indicated by the numeral 5. Preferably I bore the earth at 65 the sides of the well to provide veins 6 which assist in supplying water to the well. In this manner water is continuously maintained at a desired level.

In the well, above the veins and above the water level I insert a dome-like cap member 7. The side flange 8 of the member 7 frictionally engages with the sides of the well, but other means may be provided 75 to insure the proper retention of the cap member in the well and to provide a compartment 9 therein which is sealed to the outer atmosphere.

On the surface of the earth, adjacent or 80 to one side of the well is an air storage tank 10. Means (not shown) is provided for maintaining a desired volume of compressed air in the tank 10. Leading from the tank 10 is a valved pipe 11 connected 85 by a suitable elbow to a vertically disposed pipe 12 that passes through the cap plate 7 and enters the compartment 9 of the well. By regulating the valve, which is indicated by the numeral 13 air from the tank 10 is 90 admitted in the compartment 9 in desired volumes.

The water outlet pipe is indicated by the numeral 14 and passes centrally through the cap 7 and through the well. The lower 95 end of the pipe 14 is disposed a considerable and suitable distance above the bottom of the well and the said end has secured thereto a collar 15 that is supported on the upper end of a substantially L-shaped or 100 angle frame 16. Passing through the longitudinal branch 17 of the frame 16, in a suitable bearing opening in the upper end of the said branch is a vertically disposed rod or shaft 18. The shaft passes through 105 suitable bearing lugs 19 on one side of the outlet pipe 14 and also through a packing box 20 in the cap plate 7. The uppermost bearing for the shaft 17 is in the nature of an angle member, being located at the 110 ground level and designated, for distinction by the numeral 21. On the outer end of the

shaft 18 is a pinion 22 that meshes with a similar pinion 23 on a shaft 24, the said shaft finding a bearing in an opening through the angle arm of the bracket 21. 5 This shaft is connected with any desired mechanism (not shown) whereby a rotary motion is imparted thereto, and the turning of the shaft 24 will, of course, likewise revolve the shaft 18. On the portion of the 10 shaft 18 received in the frame 16 there is secured a toothed wheel 25 that meshes with a smaller toothed wheel 26. This last mentioned toothed wheel 26 is secured on a shaft 27 that find suitable bearings 28 in 15 the frame 16. The shaft 27 is disposed centrally with respect to the bore of the outlet pipe 14 and has its upper end received in the lower portion of the water outlet pipe 14. On the said end of the shaft 27 is a 20 pump 29. This pump is of the propellor or fan blade type, and, of course, the rotation of the shaft 18 through the medium of the interengagement of the gears or toothed wheels 25 or 26 will impart a rotary movement to the pump, and consequently materially assist the compressed air in the compartment 9 raising the water through the outlet pipe 14. The water is 25 elevated in a continuous flow and at a great volume. The construction is simple and 30 may be easily installed. Only few parts are employed and none of these parts are susceptible to breakage or disarrangement, and it is believed that the operation and advantages of the construction will be fully apparent to those skilled in the art to which 35 such inventions appertain without further detailed description.

Having thus described the invention, 40 what is claimed as new, is:—

1. In a water elevating means, a well sealed above the water level to provide an air compartment, an outlet pipe extending through the well and communicating with the water therein, means for admitting air under pressure into the air compartment, a pump in the outlet pipe below the water level, and means operative exteriorly of the well for operating said pump. 45

2. In a means for elevating water in a continuous and steady flow, a well sealed above the water level therein to provide an air compartment, a water outlet pipe passing through the well and having its lower end below the level of the water but above the bottom of the well, means for admitting air under pressure into the air compartment, means for regulating such admission of air, a rotary pump in the bottom of the water outlet pipe, and means arranged exteriorly of the well for imparting motion to said pump. 55

3. In a means for elevating water at a continuous and steady flow, a well, a cap plate secured therein above the water level 65 and providing the lower portion of the well with an air compartment, an outlet pipe passing through the cap plate and through the well, a frame on the bottom thereof resting on the bottom of the well, means for admitting air under pressure into the air compartment, regulating means therefor, a rotary pump in the lower end of the outlet pipe, and means operative exteriorly of the well for imparting motion to the pump. 75

4. In a means for elevating water from a well in a steady continuous flow, comprising a cap plate in the well above the water level and providing an air compartment therebelow, an air tank exteriorly of the well, means for compressing air therein, a pipe connection between the tank and the air compartment, a valve controlling said pipe, a water outlet pipe in the well passing through the cap plate, a frame secured 80 to the lower end of said pipe and resting on the bottom of the well, a rotary pump in the bottom of the water outlet pipe, a shaft therefor journaled in bearings in the frame, a toothed wheel on said shaft, a second shaft journaled in bearings in the frame and to one side of the outlet pipe, a toothed wheel on this shaft meshing with the first mentioned toothed wheel, and means arranged exteriorly of the well for imparting 85 motion to the last mentioned shaft. 95

In testimony whereof I affix my signature.

GRADY L. BARNETT.
